TOY UTILITY TRUCK

Joseph G. Gokey, Freeport, Ill., assignor to
Structo Manufacturing Company, Freeport, Ill.,
a corporation of Illinois

Application April 17, 1950, Serial No. 156,364

5 Claims. (Cl. 214—77)

1

This invention relates to a new and improved mechanical toy—more particularly a toy utility or dump truck.

The principal object is to provide a toy truck of the kind mentioned closely resembling the large dump trucks used in cities for garbage disposal equipment, except for example, that, in this toy the travelling dump bucket is raised and lowered by the child turning a crank, whereas in the full sized truck a hydraulic lift is employed, and so forth.

The travelling dump bucket is worked by a pair of arms pivoted on the opposite sides of the body and working through slots provided in the side walls and having concentric segmental gears provided on their pivoted ends inside the body meshing with pinions fixed on a cross-shaft mounted in the body and adapted to be turned by means of a crank operated second cross-shaft drivingly connected by pinions to the first shaft, this combination and arrangement of elements having the advantage that there are no places where a child is in danger of pinching or cutting fingers, all of the gears being concealed even though the swingable arms are necessarily exposed. The body preferably has elongated ribs embossed on the side walls thereof along which the arms can slide and be thereby guided out of marring contact with the finish on the body.

The swingable arms, in accordance with my invention are also arranged to have sliding engagement with projections provided on the sides of the free end portion of the hinged top loading door so as to swing it upwardly out of the way automatically as the travelling bucket is about to arrive adjacent the top opening for dumping, the body also having a trip projection on it next to the opening arranged to engage a lug provided on the inner side of the bucket so as to tip the bucket and dump the contents in proper timed relationship to the travel of the bucket and the opening of the top door.

The invention is illustrated in the accompanying drawing, in which—

Fig. 1 is a perspective view of a toy utility truck made in accordance with my invention, showing the bucket raised and the body in dumping position;

Fig. 2 is a central longitudinal vertical section through the dump body portion of the truck, on a larger scale, and

Fig. 3 is a sectional detail on line 3—3 of Fig. 2.

The same reference numerals are applied to corresponding parts in these three views.

Referring to the drawing, the reference nu-

2

meral 4 designates the sheet metal frame or chassis of the toy truck on opposite ends of which pairs of wheels 5 and 6 are mounted for rolling support of the toy so that it may be played with as a pull toy when the child is not using it otherwise. The sheet metal box-like dump body 7 has a bottom wall 8 in which slots 9 are provided slidably receiving lugs 10 provided on the upper ends of upwardly extending brackets 11 provided on the rear end of the frame 4, for hingedly supporting the body 7 on the frame to pivot on an axis in eccentric relation to the rear axle 24. Corner portions 12 of the lugs 10 are bent or twisted out of the plane of the lugs so as to retain the body against displacement from these lugs without interfering with the hinging action. Shoulders 13 on the lugs limit the rearward swinging movement of the body 7. An upwardly bent lug 14 is provided on the frame 4 behind the driver's cab 15 to limit the return movement of the body 7 by abutment with the bottom wall 8. A rear dump or tail door 16 is hinged to the body 7, as by rivets 17 entered through flanges 18 provided on the sides of the door, and serves as a closure for a dump opening 19 provided in the rear of the body. A slot 20 is provided in the free end 21 of the door at the middle and receives the hooked free end 21 of an elongated leaf spring 22 which is anchored by its looped inner end 23 on the rear axle 24 of the truck and attached to the rear end of the frame by engagement of a hooked end 25 of the looped portion 23 and also bears intermediate its ends, as at 26, on the rear end of the frame for support, the spring 22 being flexed for attachment to the door 16, and, prior to such attachment, in its unflexed condition, extending and being shaped approximately as indicated in dotted lines in Fig. 2. The spring 22 is therefore "loaded" when connected with the door 16, and serves the threefold purpose of (a) closing the door 16 automatically as the body 7 is swung down to the normal or loading position of Fig. 2; (b) opening the door automatically as the body 7 swings to the dumping position shown in Fig. 1, and (c) supplying the pull or spring tension necessary to swing the body 7 from its loading position to its dumping position, the pull of the spring 22 being, of course, transmitted through the door 16 to the body 7, as should be clear from inspection of Fig. 2. The stop 13 limits movement of the body 7 in the dumping direction, but spring 22 is then still under ample tension to hold the body in the dumping position and keep the hooked end 21 connected with the door 16. A leaf spring catch 27 is suitably anchored

at its lower end 28 to the front end of the body 1 and has a shoulder 29 intermediate its end which is arranged to enter an opening 30 in the vertical back wall 31 of the cab 15 to lock the body 1 releasably in the lowered or loading position. The curved free end portion 32 of the catch projects sufficiently above the top of the cab 15 to serve as a handle for release of the catch. It is in the return of the body 1 to the loading position that the stop 14 comes into abutment with the bottom wall 8 of the body, and that occurs after the shoulder 29 of the catch 27 snaps into the opening 30 to lock the body in this normal position.

The body 1 has its rear portion of arcuate form, as indicated at 60, struck with the pivotal axis 42-42 of arms 36 as an axis, so that bucket 33 carried on arms 36 can move relative to the arcuate portion 60 of the body in an arc from the lowered loading position shown in Fig. 2 to the raised dumping position shown in Fig. 1. The travelling dump bucket 33 extends substantially the full width of the body 1 and is pivotally supported at its opposite ends, as indicated at 34, on the right angled end portions 35 of the pair of arms 36 that are pivotally mounted on the opposite sides of the body 1. These arms 36 have their pivoted end portions working through slots 37 provided in the offsets 38 defined between the side walls 39 of the body proper and the integral lower apron portions 40 that extend downwardly on opposite sides of the frame 4 to improve the appearance of the toy and also form protective shields for the gear segments 41 provided on the pivoted end portions of the arms 36. These gear segments are concentric with the rivets 42 that form the pivots and fasten the arms to the side walls of the body. Ribs 43 are embossed outwardly on opposite sides of the body 1 from the sheet metal side walls 39 along which the arms 36 may slide as guides to prevent rubbing contact with the finish on the rest of the side walls and thereby insure keeping the toy looking nice much longer. Other ribs 44 at a higher elevation are provided for a similar reason, these being in alignment with the upper ends of arms 36 in their raised position so as to avoid having the finish on the side walls of the body rubbed off in that vicinity when the bucket 33 is being dumped, as in Fig. 1. Pinions 45 mesh with segments 41 and are fixed on the opposite ends of a cross-shaft 46 that is mounted in bearing holes provided in the side walls of the body 1. Another cross-shaft 47, having an integral crank extension 48 on one end, is also received in bearing holes like shaft 46 and has pinions 49 fixed on opposite ends thereof and meshed with pinions 45. In that way clockwise rotation of the crank 48 causes the clockwise movement of arms 36 required in moving the bucket 33 to the raised dumping position, and vice versa. There is, in other words, no confusion in operating the toy, because the crank is always turned in the direction of the desired motion of the arms. The gear ratio is such that a small child can easily operate the bucket, even when fully loaded with sand or dirt.

A door 50 is hinged to the top of body 1, similarly as door 16, namely by rivets 51 entered through flanges 52 provided on the opposite sides of the door. This door gravitates to a closed position closing top opening 53 through which the body 1 is adapted to be loaded by dumping from bucket 33. There are laterally bent ears 54 on the free ends of flanges 52 and these are arranged to be slidably engaged by the arms 36

when the latter are swung upwardly whereby to swing the door 50 upwardly out of the way automatically as the bucket 33 is about to arrive adjacent the top opening 53 for dumping. The door, of course, drops back later to closed position by gravity upon return of the bucket to the normal loading position shown in Fig. 2. A lug 55 suitably secured to the top wall of the body 1 in front of opening 53 is arranged in the path of and serves as a trip projection for engagement with a lug 56 provided on the inner side of bucket 33, whereby to tip the bucket and dump the contents thereof in proper timed relationship to the travel of the bucket and the opening of the top door.

It is believed the foregoing description conveys a good understanding of the objects and advantages of my invention. The appended claims have been drawn to cover all legitimate modifications and adaptations.

I claim:

1. In a toy vehicle of the character described, a body having side, top, and front and rear walls, one end portion of said body being of arcuate form with the center of the arc on a horizontal axis in the middle lower portion of the body, elongated arms pivoted at their one end on opposite sides of said body approximately on said axis, and carrying on their outer free ends a bucket extending substantially the width of the body, said body having an opening provided in the top wall, a door hinged at its one edge portion to the top of said body arranged to gravitate to closed position over said opening, means on the other edge portion of said door arranged to be engaged by at least one of said arms so as to raise the door to open position when the bucket is moved by said arms to dumping position over said opening, the lower portion of at least one of said arms being operable on the inner side of the side wall of said body, said body having a slot provided in the side wall through which the arm extends for operation, a gear segment on the pivoted end of said arm inside said body and concentric with the pivotal axis of said arms, and a crank operable pinion inside said body meshing with said segment, the crank being operable on the outer side of said body.

2. In a toy vehicle of the character described, a body having side, top, and front and rear walls, one end portion of said body being of arcuate form with the center of the arc on a horizontal axis in the middle lower portion of the body, elongated arms pivoted at their one end on opposite sides of said body approximately on said axis, and carrying on their outer free ends a bucket extending substantially the width of the body, said body having an opening provided in the top wall, a door hinged at its one edge portion to the top of said body arranged to gravitate to closed position over said opening, means on the other edge portion of said door arranged to be engaged by at least one of said arms so as to raise the door to open position when the bucket is moved by said arms to dumping position over said opening, the lower portion of said arms being operable on the inner side of the side walls of said body, said body having slots provided in the side walls through which the arms extend for operation, gear segments on the pivoted ends of said arms inside said body and concentric with the pivotal axis of said arms, a cross-shaft mounted in said body having pinions fixed on the ends thereof inside said body meshing with said seg-

ments, and a crank operable from outside said body for turning said shaft.

3. In a toy vehicle of the character described, a body having side, top, and front and rear walls, one end portion of said body being of arcuate form with the center of the arc on a horizontal axis in the middle lower portion of the body, elongated arms pivoted at their one end on opposite sides of said body approximately on said axis, and carrying on their outer free ends a bucket extending substantially the width of the body, said body having an opening provided in the top wall, a door hinged at its one edge portion to the top of said body arranged to gravitate to closed position over said opening, means on the other edge portion of said door arranged to be engaged by at least one of said arms so as to raise the door to open position when the bucket is moved by said arms to dumping position over said opening, the lower portion of said arms being operable on the inner side of the side walls of said body, said body having slots provided in the side walls through which the arms extend for operation, gear segments on the pivoted ends of said arms inside said body and concentric with the pivotal axis of said arms, a cross-shaft mounted in said body having pinions fixed on the ends thereof inside said body meshing with said segments, a second cross-shaft mounted in said body parallel to the first shaft and having pinions fixed on the ends thereof inside the body meshing with the first pinions, and a crank for turning the latter shaft operable outside said body.

4. A toy vehicle as set forth in claim 1, wherein said body has an outwardly projecting elongated rib provided on the slotted side wall in upwardly spaced relation to the slot slidably engaged by said arm working in said slot to keep the arm in outwardly spaced relation to the side wall in the to and fro swinging movement of the arm.

5. A toy vehicle as set forth in claim 2, wherein said body has outwardly projecting elongated ribs provided on the side walls thereof in upwardly spaced relation to the slots slidably engaged by said arms to space the latter outwardly relative to said side walls in the to and fro swinging movement of said arms.
